UNITED STATES PATENT OFFICE.

CHARLES M. BRENNER, OF SHREVEPORT, LOUISIANA.

VALVE-FLOAT FOR CLOSET-TANKS.

1,076,546.

Specification of Letters Patent.

Patented Oct. 21, 1913.

Application filed August 19, 1911. Serial No. 644,989.

To all whom it may concern:

Be it known that I, CHARLES M. BRENNER, a citizen of the United States, and a resident of Shreveport, in the parish of Caddo and State of Louisiana, have invented a new and Improved Valve-Float for Closet-Tanks, of which the following is a full, clear, and exact description.

My invention relates to a valve float and is more particularly adapted for closet tanks.

An object of my invention is to provide a new and improved float which is simple in construction, and positive in its action.

15 A further object of my invention is to provide a float which will have not only the permanent air chamber common to devices of this character, but in addition have a water-sealed air pocket.

20 I attain the above-outlined objects by disposing a bell-shaped member within a substantially semi-spherical member, fastening them together to form between said members a permanent air chamber, the open end 25 common to both members normally facing downward to be closed by the water rising in the tank, to form an additional air pocket.

With the above and other objects in view, 30 as will more fully hereinafter appear, the present invention consists in certain novel details of construction and arrangement of parts hereinafter fully described, illustrated in the accompanying drawings and more 35 particularly pointed out in the appended claims.

Reference is to be had to the accompanying drawings, forming a part of this specification, in which similar characters of reference indicate corresponding parts in both 40 the figures, and in which—

Figure 1 is a perspective view showing a preferred embodiment of my invention; and Fig. 2 is an enlarged vertical transverse section taken through the device shown in 45 Fig. 1.

Described more in detail, there is shown a substantially semi-spherical outer member 3, disposed within which member is a bell-shaped member 4 of less depth than the outer member to form between said members, a permanent air chamber 5. The meeting sides 6 of the two members are in contact for some material distance and the 55 edges are bent inward and then back upon themselves, to form a lock seam 7. It will

be seen that this renders the air chamber 5 hermetically sealed.

Disposed on the inside of the bell-shaped member is a brass plate 8 coacting with a similar plate 9 on the outside of the outer member, to brace the two sides together and to reinforce the float at this point. The outer plate 9 carries an internally-threaded socket 10 or other similar member to which the float rod 11 is attached by any suitable means. If desired, similar reinforcing brass plates 12 may be disposed on the outside and the inside of the meeting sides 6, to further reinforce the float, and these additional plates may be disposed on the diametrically opposite sides from the plate 8, or at any other suitable point about the sides 6.

It will be understood that this float is mounted with its open end 13 facing downward into the closed tank, so that the rising water in the tank, as the latter is filled, will close the opening 13, forming a water-sealed air pocket 14 within the bell-shaped member. This water pocket will afford a buoyancy to the float in addition to the buoyancy afforded by the permanent air space 5, so that with the same amount of material, a greater buoyancy is effected by means of my improved float than by the floats now in common use.

While a preferred embodiment of the invention has been described, it is to be understood that many changes could be made in the above construction and many apparently widely different embodiments of this invention could be made without departing from the scope thereof. It is intended that all matters contained in the above description or shown in the accompanying drawings, shall be interpreted as illustrative and not in a limiting sense. It is also to be understood that the language used in the following claims is intended to cover the full scope of the invention and is not to be given any narrower construction than the prior art demands, and that materials, sizes and relativities of parts are non-essential, except as called for in the claims.

Having thus described my invention, I claim as new and desire to secure by Letters Patent:

1. A valve float for closet tanks, comprising a substantially semi-spherical member, and a bell-shaped member disposed within the semi-spherical member, both of said

members having their open ends facing in the same direction, both of said members being imperforate and the inner member having a curved top and an approximately 5 cylindrical body portion the outer face of which, from its open end approximately throughout its height, engages the corresponding inner face of the semi-spherical member, the said members being fastened 10 together at their open ends and the inner member being of less depth than the outer member to form between them a hermetically sealed air chamber, the open end of the float facing downward and adapted to 15 engage the water in the tank to form a closed water-sealed air pocket in said inner member, co-acting reinforcing members disposed respectively on the inside of the inner member and the outside of the outer member 20 at the meeting sides of said members, and a float connected with one of the reinforcing members.

2. A valve float for closet tanks, comprising a pair of hollow imperforate members 25 each having an open end, one of said mem-

bers being of less depth than the other member and disposed within the same, the sides of said members at the open end portion being in contact and the edges of said members at the open ends being fastened together by a lock seam to form between said members a permanently sealed air chamber, and to reinforce the said members at their open ends, the open end of the float being adapted to be closed by the water in the 30 tank to form a closed water-sealed air pocket in said inner member, plates disposed respectively on the inside of the inner member and the outside of the outer member at the meeting sides of said members to 35 reinforce the same, and a float stem connected with one of the outer plates.

In testimony whereof I have signed my name to this specification in the presence of two subscribing witnesses.

CHARLES M. BRENNER.
